CLAIM

The ornamental design for a marking device, as shown and described.

DESCRIPTION

FIG. 1 is a top, front, right side perspective view of the marking device;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

In one embodiment, the broken lines shown are included for illustrative purposes only and form no part of the claimed design. For example, the broken lines include portions of the handle such as a screen, various buttons, a trigger, and a heat sink on the underside of the handle, as well as the battery cover and a paint can positioned within a paint holder.
